UNITED STATES PATENT OFFICE.

HARRY R. HUGHS AND WADE C. HUGHS, OF WALHALLA, SOUTH CAROLINA.

FIRE-ALARM SYSTEM.

1,244,332.

Specification of Letters Patent. Patented Oct. 23, 1917.

Application filed August 30, 1916. Serial No. 117,751.

To all whom it may concern:

Be it known that we, HARRY R. HUGHS and WADE C. HUGHS, citizens of the United States, residing at Walhalla, in the county [5 of Oconee and State of South Carolina, have invented new and useful Improvements in Fire-Alarm Systems, of which the following is a specification.

This invention relates to improvements in 10 fire alarm systems and has particular application to an automatic fire alarm system.

In carrying out the present invention, it is our purpose to provide an automatic fire alarm system wherein by means of thermostatic circuit closers, located in the various compartments of the protected structure, a central alarm will be sounded in the protected structure and the location of the compartment in which the fire is present indicated, and a signal given at the city fire 20 station and the location of the structure in which the fire is present indicated so that proper steps may be taken to extinguish the conflagration.

It is also our purpose to provide a system 25 of the type set forth which will embrace the desired features of simplicity, efficiency and durability, and which will operate effectively when conditions warrant.

With the above and other objects in view, the invention consists in the construction, combination and arrangement of parts hereinafter set forth in and falling within the scope of the claims.

In the accompanying drawings;

Figure 1 is a diagrammatic view of our improved fire alarm system showing the circuit connections.

Fig. 2 is a plan view of one of the circuit 40 closers.

Fig. 3 is a front elevation of the indicating apparatus in the protected structure.

Fig. 4 is a vertical sectional view on the line 4—4 of Fig. 3.

Fig. 5 is a cross sectional view on the line 5—5 of Fig. 3.

Fig. 6 is a front elevation of the indicating apparatus located at the city fire station.

Fig. 7 is a sectional view on the line 7—7 of Fig. 6.

Fig. 8 is a cross sectional view on the line 8—8 of Fig. 6.

Located in each compartment of the protected structure is a circuit closer 1 comprising a base plate 2 adapted to be fastened

to a suitable support. Secured to the base plate 2 and projecting outwardly therefrom is a binding post 3 and connected to the binding post 3 is one end of a spring contact finger 4. Arranged in the path of movement of the other end of the finger 4 is a contact post 5, while secured to the base plate adjacent to the contact post 5 is a receptacle 6 and disposed in the receptacle 6 is one end of a capsule 7 formed of paraffin or the like and having the other end in engagement with the finger 4. This capsule 7 acts to hold the contact finger 4 normally out of engagement with the post 5, as illustrated in Fig. 2 of the drawings. When, however, the capsule is melted, owing to the presence of heat, the finger 4 is relieved of the restraint thereof and springs against the contact post 5.

Located at some central or conspicuous position in the protected structure is a local indicating apparatus 8 embodying a substantially rectangular casing 9 having the names of the various compartments in the 75 protected structure inscribed on the front wall thereof and arranged one above the other, as shown at 10. Formed in the front wall of the casing 9 at the corresponding ends of the respective inscriptions are openings 11 and seated in the respective openings are lamps 12. Behind the front wall adjacent to the respective lamps 12 are electroresponsive devices 13 controlling horizontal shafts 14 respectively and mounted upon each shaft 14 behind the front wall of the casing is an arm 15, while secured to the outer end of each shaft 14 and disposed upon the outer side of the front wall of the casing is an indicating arrow 16. The arms 15 and the arrows 16 are normally disposed in a vertical position and upon the energization of any one of the electroresponsive devices 13, the armature 13' moves to release the arm 15 and the corresponding shaft 14 is rotated to turn the arm 15 and the arrow 16 to a horizontal position, the arrow pointing to the corresponding inscription on the front wall of the casing to indicate the location of the conflagration. Mounted upon the 100 casing 9 is an electrically operated bell 17. Arranged behind the front wall of the casing 9 are vertical bus bars 18 and 19 spaced apart from each other and connected to the bus bars 18 and 19 and projecting toward 110 each other are contact lugs 20 normally spaced apart and arranged adjacent to the

respective electroresponsive devices 13. These lugs 20, 20 adjacent to each electroresponsive device 13 are adapted to be bridged by a bridging strip 22 carried by 5 the adjacent arm 15 when the latter swings to vertical position under the action of the electroresponsive device. A switch 19' is connected across the bus bars so that the circuit including such bars may be closed by 10 hand when desired or necessary.

A source of electrical energy is shown at 23, and connected to the opposite sides of such source and extending throughout the protected structure are feed wires 24. Connected across the feed wires 24 and in series 15 with one another are the corresponding circuit closers, electroresponsive devices 13 and lamps 12, the connection between each circuit closer and the electroresponsive device 20 being such that the inscription on the front wall of the casing adjacent to the electroresponsive device corresponds to the location of the circuit closer. The bell 17 is preferably connected in series with each set embodying a circuit closer, electroresponsive 25 device and lamp, as clearly illustrated in Fig. 1 of the drawings.

Located at the city fire station is a "central" indicating apparatus embodying a casing 25 having the names or locations of the 30 protected structures inscribed on the front wall thereof and arranged one above another. Formed in the front wall of the casing 25 at one end of each inscription is an 35 opening 26 and disposed within the opening 26 is an electric lamp 27, while arranged within the casing 25 adjacent to the respective lamps 27 are electroresponsive devices 28 whose armatures 13' release arms 15 40 carrying arrows 16 like those described, and arranged upon the outer side of the front wall of the casing 25. These arrows are also normally disposed in vertical position and capable of movement to horizontal position 45 so as to point to the respective inscriptions on the front wall of the casing and connected with a suitable restoring device. Each electroresponsive device 28 is connected in series with the adjacent lamp 27 50 and each set of these translating devices corresponds to an indicating apparatus located in a protected structure, and this set of translating devices is connected in circuit 55 with a source of electrical energy and the bus bars 18 and 19, as clearly shown in Fig. 1 of the drawings. Mounted upon the casing 25 is an electric bell 29 that is connected in series with each set of translating devices 28 and 28, as shown in Fig. 1.

60 In practice, when a fire occurs in a compartment of the protected structure, the rising temperature melts the capsule 7, thereby closing the circuit through the corresponding electroresponsive device 13 and lamp 12 upon the energization of the elec- 65

troresponsive device 13, the arm 15 bridges the contact lugs 20, thereby closing the circuit through the bus bars 18 and 19 to the corresponding electroresponsive device 28 and lamp 27 in the fire station. Simultaneously with the closing of these circuits, the bells 17 and 29 sound, thereby warning the authorities of the conflagration. Upon the movement of the shaft 14 to swing the arm 15 to close the circuit to the fire station, the arrow 16 points to the inscription on the casing indicative of the location of the particular compartment, while the arrow 29 at the fire station points to the inscription indicative of the protected structure in which the fire is present. 70

While we have herein shown and described the preferred form of our invention by way of illustration, we wish it to be understood that we do not limit or confine ourselves to the precise details of construction herein described and delineated, as modification and variation may be made within the scope of the claims and without departing from the spirit of the invention. 85

We claim:

1. In a fire alarm system, an indicator arranged in a protected structure and embodying a casing having the front wall thereof inscribed with the names of the compartments of the protected structure, arrows pivoted for swinging movement to point to said inscriptions respectively, electroresponsive devices for actuating said arrows, lamps adjacent to said electroresponsive devices 95 respectively, circuit closers located in the respective compartments of the protected structure adapted to operate under the action of heat, circuit connections between each circuit closer and the corresponding electroresponsive device and lamp, an indicating apparatus located at a fire station remote from the protected structure, bus bars in the first-mentioned casing, contact lugs on said bus bars arranged adjacent to said electroresponsive devices respectively, and an arm connected to each arrow and movable therewith to bridge the adjacent contact lugs and circuit connections between said bus bars and the indicator at the station whereby the latter will be operated to indicate the location of the protected structure in which the fire is present. 100

2. In a fire alarm system, an indicator arranged in a protected structure and embodying a casing having the front wall thereof inscribed with the names of the compartments of the protected structure, arrows pivoted for swinging movement to point to said inscriptions respectively, electroresponsive devices for actuating said arrows, lamps adjacent to said electroresponsive devices respectively, circuit closers located in the respective compartments of the protected structure adapted to operate under the ac- 110 115 120 125 130

tion of heat, circuit connections between each circuit closer and the corresponding electroresponsive device and lamp, an indicating apparatus located at a fire station 5 remote from the protected structure, bus bars in the first-mentioned casing, contact lugs on said bus bars arranged adjacent to said electroresponsive devices respectively, an arm connected to each arrow and movable therewith to bridge the adjacent contact lugs and circuit connections between

said bus bars and the indicator at the station whereby the latter will be operated to indicate the location of the protected structure in which the fire is present, and a bell 15 connected in circuit with all of said circuit closers and adapted to sound upon the closing of any one of said circuit closers.

In testimony whereof we affix our signatures.

HARRY R. HUGHS.
WADE C. HUGHS.
